TRAFFIC SIGNAL SYSTEM

Charles B. Watson, Omaha, Nebr., assignor of
forty-nine percent to Fay G. Johnson, Omaha,
Nebr.

Application January 17, 1935, Serial No. 2,232

4 Claims. (Cl. 177—329)

This invention has to do with the art of traffic control signals of the type customarily provided at the corners of street intersections and which alternately display green and red lights for indicating to traffic and pedestrians the direction of traffic movement or flow.

The existing form of intermittent signals generally in use for traffic control or regulation are often a source of confusion and are responsible for many of the accidents on an intersection, resulting in personal injury and property damage due to the lack of facilities for instantaneous perception of the relative control factors which will enable the driver to concentrate upon the driving hazards. When approaching an intersection having a "proceed" indication neither driver nor pedestrian has any knowledge of the length of time since the beginning of the indication and proceeds, often only to have the indication unexpectedly change to stop for his direction and proceed for the opposite direction, resulting in a forced clearance against opposing traffic and stranded pedestrians with the resulting confusion and hazard.

It is therefore an object of my invention to provide a positive, continuous, visual, informative control system to minimize intersection hazards and having a threefold, instantaneous and simultaneous visual indication showing the existing direction indication, the elapsed time since the previous indication and the time that is to elapse before the succeeding indication.

Another object is to increase the amount of visual indication by the use of comparatively long indicators which have no dark moments between changes.

Other objects are to provide an illuminant having a high atmospheric penetrating characteristic in order that the indication may be seen from a greater distance; to provide a system having a continuously moving indicator with a relative difference in intensity for the psychological effect of concentrating the attention upon the cycle of operations; to provide a flexible control system whereby different rates of indication are available such as varying the length of the time period of the display of the respective tubes of the indication for a north and south movement from that of the east and west movement and vice versa, also varying of the time period in the separate individual indicators as well as groups of indicators; to provide a flexible system whereby signal units may be synchronized in groups or individually controlled; and to provide an improved signal system with a lower operating cost,

The foregoing and other aims and objects will be apparent from the detailed description hereinafter appearing when taken in conjunction with the accompanying drawings, wherein:

Figure 1 is a side view of the head of my traffic signal having signals on two sides, one side only being shown.

Figure 2 is a sectional view taken on line 2—2 of Figure 1 showing one of the illuminating tubes.

Figure 3 is a section of an illuminating tube 10 showing a modified form of electrode.

Figure 4 is a sectional view of the head of the signal taken on line 4—4 of Figure 1 but illustrating an octagonal signal head having four sets of signal indicator tubes.

Figure 5 is an enlarged sectional view taken on line 5—5 of Figure 6 to illustrate the light concentrating element around the electrode.

Figure 6 shows a portion of a tube adjacent an electrode as seen from the rear, said view is enlarged to show the built up shoulder of glass which forms the light concentrating element around said electrode.

Figure 7 is a diagrammatic view of the wiring system having four sets of indicating tubes of 25 five electrodes each.

Referring more particularly to the drawings reference numeral 10 indicates a standard or post upon which a signal head 11 is supported. In my preferred embodiment the head is octagonal in cross-section as shown in Figure 4. The head 11 is provided with panels 12, oppositely disposed, only one of which is shown in Figure 1, on which is provided vertical tubes R13 and G13, Figure 1, filled with a gas such as neon or the like and spaced horizontally apart, tube R13 producing a red light and tube G13 producing a green light, when a suitable electric current is passed therethrough. It is desirable that the lights on a signal panel be visible from only one direction, that facing the flow of traffic, and invisible from all other directions. To shield said tubes from sight from any but the direction of traffic flow they are recessed in channels 14 which are enlarged at their open ends to increase the width of the luminous signal light and said channels may be coated with any suitable reflecting material to increase the brilliance of the signals.

Each tube is provided at its top and bottom with a rearwardly extending pocket 15 and 16 respectively in which electrodes 17 and 18 respectively are fixed and between said top and bottom pockets are provided a plurality of intermediately spaced pockets 19 each of which is provided with an electrode 20. Electricity to energize the gas

in the tubes is taken from the secondary 21 of a transformer 22 which is supplied with electric current from any suitable source such as an ordinary commercial circuit 23 carrying 110 volts 5 and having a switch 23a therein. One side of the secondary 21, which I shall call the low side 24, is connected to the lower electrodes 18 of the tubes and the other or high side 25 is connected to an arm 26 of a distributor or flasher 10 27 which is driven by an electric motor 28 of suitable speed.

The distributor is provided with a plurality of annularly spaced contact points 29 mounted on the insulated base thereof, said points being connected in groups, indicated in Figure 7 by large capital letters R G and small capital letters R G, the arm being adapted to rotate and successively contact the contact points 29. The signal head is provided with four signal panels with signals 15 for controlling traffic from four directions and the tubes thereof are identified by large capitals R1, R2, G3 and G4 and small capitals R5, R6, G7 and G8 corresponding to the tubes similarly identified in Figure 7. In the embodiment of my 20 invention herein illustrated the group of tubes indicated by the large capital letter prefixes are lighted, progressively darkened and extinguished together, likewise the tubes identified by the small capital letter prefixes. In order to more 25 clearly show the wiring system the tubes in Figure 7 are provided with only five electrodes instead of twenty electrodes provided in the tubes R13 and G13 of Figure 1. With the arm in the position shown in Figure 7 current is supplied to 30 the upper electrodes of the respective tubes in the large capital letter series and at the same time current is supplied to the last or lower intermediate electrodes of the small capital letter series tubes thereby lighting the last or lower 35 section of said tubes. This is accomplished by connecting the first contact point of the large capital letter series or group with the last contact point of the small capital letter series or group with a wire 30. Any of the common expedients for operating tubes of different resistances 40 in parallel may be used to insure energization of both tubes. As the arm is advanced to the next contact point of the large capital letter series the tubes of said series are lighted from 45 the first intermediate electrode, adjacent the top electrode, downward to the bottom thereof while the tubes of the small capital letter series are extinguished entirely. Then as the arm advances, progressively making contact with the 50 succeeding contact points the current is supplied to respective intermediate electrodes along the tubes so that with each succeeding contact point contacted by the arm the light in the illuminated tubes drops downward and extends from 55 the electrodes connected with the contact point of the distributor contacted by the arm to the bottom of the tubes until the last section is illuminated. This section remains illuminated while 60 the following series of tubes is illuminated the 65 full length due to the last contact point of the large capital letter series being connected with a wire 31 to the first contact point of the small capital letter series thus causing an overlapping in the sequence of the lighting at the time of 70 signal change and eliminating any dark moments between the illumination of tubes of a following series and the extinguishing of the tubes of a previously illuminated series, and providing continual, uninterrupted lighting of the 75 indicator signals.

In order to clearly indicate the upper limit of the tubes an auxiliary tube 32 is provided around the signal head adjacent the upper ends of the tubes, said auxiliary tube giving off a colored light, preferably blue, of a different color from the colors given off by the signal tubes. The auxiliary tube 32 thus makes easy the determination of the relative length of time since the last signal change and the relative length of time before the next signal change. 10

A modified form of electrode is shown in Figure 3 wherein the end 35 is somewhat down-turned to positively eliminate light above said electrode and form a sharp line of demarcation 15 of the light at this point.

To increase the intensity of the light at said point and for the purpose of attracting and holding the attention upon the cycle of operation a glass shoulder 34 is built up around the pockets for the electrodes at the junction of said pockets 20 and the tube. The shoulder concentrates and intensifies the light in the tube locally and reflects said concentrated light forwardly to form a sharp luminous point at the limits of tube 25 illumination.

It is to be understood that the signal tubes may be provided with any desired number of electrodes spaced in any suitable manner. The distributor may be placed in an individual signal 30 head for controlling or regulating the signals thereof or one distributor may be used to control a group of signal heads. It is also to be understood that the relative length of the time period for groups of tubes may be varied relative to each group as well as the length of the time period 35 of individual tubes in a single series or group. This may be done to give preference to traffic in certain directions over traffic from other directions.

Having thus described my invention what I 40 claim is:

1. In a traffic signal system for controlling traffic at street intersections and the like, the combination, a signal support, a plurality of extended electrically illuminable indicators on the support, said indicators being straight and in parallel association relative to each other, the respective indicators being of different colors and adapted to illuminably and colorably control the flow of traffic by alternately signaling traffic to stop and proceed, each of said tubes being adapted to be illuminated the full extent thereof and to have the illuminated portion progressively decreased in extent, and distributing means 45 adapted to distribute electric current from a suitable source of electric supply to the indicators and to illuminate alternately the stop and proceed indicators and to progressively decrease the extent of the respectively illuminated portions thereof, and in respect to indicators facing the same line of traffic said indicators being alternately illuminated their full length while a portion of a previously illuminated indicator is still illuminated. 55

2. In a traffic signal system for controlling traffic at street intersections, the combination, a signal support, a plurality of vertically extending electric illuminable gaseous discharge tubes on the support, said tubes being straight and in parallel association and adapted to illuminably and colorably control the flow of traffic by alternately signaling traffic to stop and to proceed, each of said tubes being adapted to be illuminated the full extent thereof and to have the illuminated portion uniformly decreased in 60 65 70 75 80 85 90

extent, means for increasing the intensity of the luminescence at the limits of luminosity of the tubes, and distributing means adapted to distribute electric current from a suitable source of supply to the tubes and to alternately illuminate the stop and proceed tube and to progressively and uniformly decrease the extent of illumination of the respective tubes.

3. In a traffic signal system for controlling traffic at street intersections, the combination, a signal support, a plurality of straight, vertically parallel, electrically illuminable indicator tubes on said support spaced horizontally apart and adapted to colorably control the flow of traffic by alternately signaling traffic to stop and to proceed said tubes being of different colors upon illumination thereof, each of said tubes having an electrode in its upper and lower ends and a plurality of intermediately spaced electrodes, and distributor means adapted to distribute electric current from a suitable source of supply to the electrodes of the tubes, said distributing means being adapted to distribute current alternately to stop and proceed tubes to illuminate the entire length of the respective tubes and then progressively shorten the illuminated portion thereof from one end by supplying current to the intermediate electrode in ordered sequence from said end and illuminate alternate

tubes facing the same line of traffic while a portion of the companion tube is still illuminated.

4. In a traffic signal system for controlling traffic at street intersections, the combination, a signal support, a plurality of straight, vertically parallel, electrically illuminable indicator tubes on said support spaced horizontally apart and adapted to colorably control the flow of traffic by alternately signaling traffic to stop and to proceed said tubes being of different colors upon illumination thereof, each of said tubes having laterally extending electrode pockets at the upper and lower ends and a plurality of intermediately spaced laterally extending electrode pockets, shoulders at the junction of the pockets and tube adapted to locally reflect light, electrodes in each pocket, and distributor means adapted to distribute electric current from a suitable source of supply to the electrodes, said distributing means being adapted to distribute current alternately to stop and proceed tubes to illuminate the entire length of the respective tubes and then progressively shorten the illuminated portion thereof from one end by supplying current to the intermediate electrode in ordered sequence from said end and illuminate alternate tubes while a portion of the companion tube is still illuminated.

CHARLES B. WATSON.
